NATHAN H. SUREN, OF NEEDHAM, MASSACHUSETTS, ASSIGNOR TO THE GAMEWELL COMPANY, OF NEWTON UPPER FALLS, MASSACHUSETTS, A CORPORATION OF MASSACHUSETTS.

SIGNALING APPARATUS.

Application filed September 6, 1924. Serial No. 736,361.

This invention relates to signaling apparatus suitable for use in signal systems, and particularly to non-interference signal transmitters for use in signaling systems which are normally conditioned for metallic circuit operation and have provision for operation through a normally open ground return in the event of a broken metallic circuit.

Such signaling systems ordinarily comprise a current source, manifesting mechanism, and a plurality of signal transmitting stations each having circuit-breaking and circuit-grounding mechanism as well as electromagnetically controlled non-interference mechanism. In such systems, switching means are commonly provided whereby the current source is normally connected, through the manifesting means, with the metallic circuit which includes the transmitting stations, and whereby—in the event such circuit is disabled by breakage thereof—one terminal of such current source may be grounded and the two ends of the normal metallic circuit connected in parallel through manifesting mechanism, with the other terminal of such source.

In order that the electromagnetic non-interference mechanisms of the transmitting stations shall enable signal formulation to be effected from any one of such stations when the metallic circuit is broken at one side or the other of such stations, such mechanism has been provided with two electromagnet windings arranged for serial connection in the normal metallic-circuit current-path, and a circuit controller comprising a pair of normally closed code signaling contacts are connected in such current path between the non-interference magnet windings; a grounding contact being associated with said circuit controller whereby both of the contacts of such controller may be grounded during each closure thereof incident to the formulation of a signal. In this way, provision is made so that, in the event the normal metallic circuit is broken and the switching means associated with the current source is conditioned to ground one terminal of the current source and connect the other terminal of the current source to the ends of the normal metallic circuit in parallel.—energization of the non-interference electromagnet will be effected at any actuated signal box because current flow

through the grounding contact of such box will pass through one or the other of the electromagnet windings of the non-interference mechanism, and thereby cause such mechanism to function in the intended manner.

For reasons well understood by those skilled in this art, the ground connections of such transmitting stations should be ineffective other than when such stations are set for the transmission of a signal and, to this end, circuit controlling means—apart from the code signaling contacts—have heretofore been provided in such boxes for normally interrupting the ground connections thereat and for closing such connections at signaling stations when set for signal formulation. An example of such circuit controlling means is shown in Patent No. 1,196,732, to Lewis Degen, dated August 29, 1916.

In signaling systems equipped with signaling apparatus such as that just described, the mechanism of signal transmitting stations is likely to remain unused for long periods of time and, as a result, attempt to establish circuit connections between normally separated contact members may prove ineffective when first attempted, even when repeated actuations of such contacts would bring about an effective connection between them. Furthermore, for reasons well understood by those skilled in this art, it has been found very desirable to minimize the number of separate places at which breaks may be established in vital signaling paths, especially as to breaking points which stand normally open.

It is, therefore, an important object of this invention to provide signal transmitting mechanism, of the type referred to, in which the arrangement of vital signaling current paths is such as to minimize the number of places at which they may be interrupted, and in which the action of such mechanism in closing normally open contacts will be so repeated that connections will thereby be rendered effective and improved after a plurality of actuations thereof, even when not fully effective upon initial actuation thereof.

In the use of signaling systems comprising signal transmitting stations with electromagnetic non-interference mechanism arranged as hereinbefore referred to, it has

been found that although the non-interference mechanism of such stations would function as intended when the normal metallic circuit current path was effective and also 5 when the switching means associated with the current source was abnormally conditioned during interruption of such path at one side or the other of any such station. On the other hand, it has become customary, 10 in such signaling systems, to accomplish one or the other of two results when such switching means is abnormally positioned; either grounding the battery or other current source of the circuit midway (electrically) 15 between its terminals so that one-half of the total electromotive force of such source will be effective between either terminal and the ground connection, or grounding one terminal of the current source and connecting both 20 ends of the broken line through suitable receiving instruments to the ungrounded terminal of such source. In systems in which it has been attempted to restore operability of a broken line by grounding the electrical 25 center of electromotive force of the current source, in accordance with the first of the arrangements just referred to, it has been found that it not infrequently happens that the partial electromotive force thus available for signal transmission is inadequate. 30 In this connection, it should be remembered that the electrical characteristics of many signaling circuits are such that the preponderance of resistance is in the outside line; 35 so that, if it so happens that a break occurs near one end of the circuit, a mere half of the electromotive force needed for signaling over the entire circuit proves insufficient for signaling to the most distant stations from 40 an unbroken end of the circuit, such inadequacy being materially supplemented by the fact that the ground connections utilized under such emergency conditions are frequently of a resistance equal to a major fraction 45 of the normal resistance of the entire circuit. Suggestions that the emergency ground connection at the current source be applied nearer to one terminal than the other (for the purpose of overcoming such a condition) have not proved helpful, because the 50 location of a break, relative to the normal potential gradient along the circuit, is usually unknown to the operator having occasion to apply such a ground connection, at 55 the time a break occurs in the circuit. In systems in which such switching means accomplishes the second named one of the results just referred to, it is obvious that when such switching means remains abnormally 60 conditioned following the repair of a break in the normal metallic circuit, the non-interference mechanisms of such boxes fail to function in the intended manner and the transmission of their signals is not effected 65 because the only effective current paths then

provided upon the establishment of the ground connection at any such box, incident to attempted signal formulation thereby, are those from one terminal of the battery over the two sides of the metallic circuit in parallel, with the result that the current flow through one of the electromagnet windings of the non-interference mechanism will be in reverse direction to that which occurs during normal metallic circuit operating conditions, and, therefore, each of said windings tends to neutralize the other.

In other words, those attempting to establish a signal circuit which would afford facilities for maintaining service from non-interference code signal stations, in the event of rupture of the line wire, through the utilization of ground connections at such stations, have heretofore been confronted with the alternative of hazarding losses of alarms under either one or the other of two sets of circumstances, depending upon the arrangement of the switching means utilized in connection with the current source for bringing about restoration of service during broken line conditions. When the so-called "center ground" arrangement has been applied to the current source, signals have been lost when the current path from the source to an actuated box included resistance greater than that through which signal transmission could be dependably effected with but one-half of the normal voltage of the current source; and it has been found to be impracticable to effectively offset this danger by so increasing the normal potential of such a current source that one-half of such potential will suffice for effective signal transmission from a station, operating through the ground, from such portion of the circuit as to include practically all of the line wire between the current source and such station. The reason for such impracticability is that such increase should be to more than double the electromotive force needed for signal transmission under normal circuit conditions (so as to provide for ground connection resistances) and an increase of such magnitude in electromotive force tends to objectionably affect the non-interference function because it involves a corresponding variation in line current intensity between normal metallic circuit conditions and those of alarm transmission through a ground connection. The objections to so wide a range of operating current conditions are generally well understood by those skilled in this art, so it is believed that it will suffice to here recite but one of such objections; i. e., the fact that the type of non-interference signal stations ordinarily used in such systems depend for the attainment of their non-interference function upon movement of the so-called "non-interference armature" out of the nor-

mal effective range of their magnets, and such effective range is so extended by using an electromotive force under normal circuit conditions which is double that needed for effective signal transmission that such armatures are likely to then so act in response to signaling closures from other stations as to defeat their intended function. If, on the other hand, the ends of the broken circuit are connected to the ungrounded terminal of a grounded current source having sufficient potential to dependably effect the transmission of a signal over all or any portion of a normal signaling circuit, loss of signals will result in the event of the operation of any signaling station in such circuit, following repair of the break therein, unless and until the switching means is operated to restore the current source to its normal series relationship to the circuit.

The opportunity thus afforded for loss of all signals from the circuit affected, frequently assumes serious importance; as, for example, in the public fire alarm system of a comparatively small municipality. Such relatively small systems frequently are dependent upon the services of one man, both for supervision and operation of controlling switches at headquarters and for maintenance and repair of outside circuits; so that, especially following a severe storm, such a man may be engaged in outside line work for hours, after having visited headquarters and abnormally conditioned the switching means there provided; and, while so employed, will close all breaks which he finds in his circuits, thereby (sometimes without immediate realization that he is so doing) conditioning the outside lines of the circuits for resumption of normal metallic circuit operation.

In such systems, when constructed in accordance with the hereinbefore described prior art, such a man, upon closing the final break in any given circuit, must either neglect breaks in other circuits while he goes to headquarters for the purpose of restoring normal circuit operating conditions in the circuit he has closed or take the chance of losing a signal from some station of the circuit the breaks in which he has repaired, until he has repaired the breaks in other circuits. In this connection it should be remembered that abnormal conditioning of the switching means at headquarters will not, if there are two or more breaks in the circuit, restore operability to signaling stations situated in such circuit between those breaks, so that if such a man returns to headquarters every time he has reason to believe that he has closed a circuit, he may thereby incur the hazard of losing signals from any one of a larger number of stations for a longer time than if he remained away from headquarters until he had inspected the entire line and

satisfied himself that he had repaired all circuit breaks.

It is, therefore, a further important object of this invention to provide non-interference mechanism for such transmitting stations which is so constructed and arranged as to assure intended functioning thereof both when the metallic circuit current path is open and when said path is closed, while the switch associated with the current source is abnormally positioned, as well as when the metallic circuit current path is closed and said switch is normally positioned.

Other objects are to simplify the apparatus of such transmitting stations, to render them more durable and more reliable in operation, and to facilitate and decrease the cost of manufacture of such apparatus.

Still other objects, together with their inherent advantages, will be in part obvious and in part hereinafter specifically set forth.

For the attainment of the foregoing objects, this invention consists of certain features of combination, form and arrangement of parts which will be most readily understood by reference to the embodiment thereof described in detail by the following specification and shown in the annexed drawing, where like reference characters denote similar parts, and in which—

Figure 1 is a front elevation of the signaling train of a well-known and widely used form of fire alarm signal box, in its case, with an illustrative embodiment of this invention applied thereto;

Fig. 2 is a diagrammatic view of a signal circuit showing the manner of connecting the significant parts of the mechanism of Fig. 1 therein; the parts being shown as positioned when the circuit is conditioned for signal transmission through the ground path, and the non-interference magnet being shown as turned 90° from the position indicated by Fig. 1, so as to facilitate representations of the paths of magnetic flux between the poles thereof;

Fig. 3 shows the signal box parts of Fig. 2, in the respective positions assumed thereby during a circuit interruption incident to signal formulation thereby;

Fig. 4 shows the parts of Fig. 3 in the respective positions assumed thereby during operation of the signaling train without control of the signaling circuit, as when such circuit is controlled by some other box; and

Fig. 5 is an end elevation of the non-interference electromagnet of Figs. 1, 2, 3 and 4.

The signaling train of Fig. 1 may be briefly described as comprising a main wheel 21, arranged for actuation by the spring 22 to drive the code wheel 23 at a speed governed by the escapement mechanism comprising the wheel 24 and pallet 25. A detent member, comprising the lever 26, is arranged to cooperate with the flange 27 car-

ried by the wheel 21 in the usual manner, so that said mechanism is normally held at rest and so that momentary elevation of said lever will condition said train to permit a desired cycle of the operation thereof in the course of which said wheel 21 will so rotate as to cause a suitable number of revolutions of the code wheel 23, and hence rounds of the intended signal; following which said 10 lever may move downwardly to its normal position and thereby cause the train to be again brought to rest, unless such movement of said lever is prevented by manipulation of the manually operable, so-called "pull handle" 28, which is provided for facilitating actuation of the lever 26 to release the mechanism, or by other means such as will be presently described.

The signaling lever 29 is pivotally supported at 30, and carries the projection 31 for cooperation with the code wheel 23. The tail 32 is carried by and moves with said lever 29; the free end of said tail being arranged for cooperation with the pin 33 carried by the wheel 21 for holding said lever 29 away from said code wheel when the mechanism is at rest and, immediately after the starting thereof, until the first tooth or projection of said wheel has moved into the 30 path of said projection 31.

The lever 40 is pivoted at 41 and carries the armature 42 at an end thereof. The opposite end of said lever 40 carries a rearwardly extending projection 43 for cooperation with the pin 44 carried by the wheel 45 which rotates with the code wheel 23. As indicated by the dotted line directly above the left hand edge of the pin 44, said projection is so formed that, when the lever 40 is in the position which it occupies when the armature 42 is in fully attracted position, said pin may pass to the right of said projection; and said projection extends to the left of said dotted line coextensively 45 with the contour of the lever 40, as shown,— so that when said lever is in the position which it occupies when the armature 42 is in fully retracted position, said projection will be disposed within the arc described by 50 the revolution of said pin around the axis of the wheel 45 and will thus avoid engagement thereby, and so that when said lever occupies an intermediate position, to which it may be moved as hereinafter more fully 55 explained, said projection will be in the path of said pin for engagement thereby to move said lever to carry the armature 42 to its normal attracted position.

The pin 46 is carried by the lever 40 in 60 such position as to be adapted for cooperation with the free end of the detent lever 26 as hereinafter more fully explained, and the retractile spring 47 is suitably connected with said lever 40 and is of such strength 65 as to prevent movement of said lever in re-

sponse to the pull of the electromagnet when the armature 42 is in fully retracted position.

The signaling contacts 48 and 49 are arranged for actuation in the usual manner by the signaling lever 29; and the usual protective shunt contacts 51 and 52 are carried by the insulating blocks 53 and 54, respectively; said block 53 being fixed upon the frame plate 50 and said block 54 being so mounted upon the lever 26 that when said lever is positioned for restraining operation of the signaling train the contact 52 will engage the contact 51 and when said lever is positioned to permit operation of said train said contacts will be separated.

The faces 55 and 56 and the shoulder 57 are so formed in the free end of the lever 26 that, when said lever is positioned for restraining operation of the signaling train, said face 55 will so engage said pin 46 as to prevent movement of the lever 40 from attracted to retracted position; said face 56 is so positioned that movement of the detent lever 26 from its fully elevated position toward the position where it will cause the running of the signaling train to be arrested will cause said face to act through the pin 46 to so move the lever 40 as to bring the projection 43 carried thereby into the path of the pin 44; and the shoulder 57 is so positioned that, when the pin 46 is resting against the face 55, said shoulder will engage said pin during movement of the detent lever 26 away from its fully elevated position before such movement has proceeded to a point such as will cause the running of the signaling train to be arrested.

A pin 58 is carried by the armature lever 40 in such relationship to the extension 59 forming part of the signaling lever 29 that said signaling lever may assume the position which permits the contact 48 to move away from the contact 49 only while said armature is in its normal or attracted position, and such that said armature lever will be 105 permitted to move to its abnormal or retracted position only while the contact 48 is in engagement with the contact 49.

The signal transmitting apparatus thus far described is the signaling train of a 110 well-known form of so-called "perfect non-interference and succession" fire alarm box, and is here shown and described as typifying one of the forms of signal transmitting apparatus to which this invention may be 115 applied, and it will be understood by those skilled in this art that this invention is suited for corresponding or similar application to other forms of signaling trains.

In applying this invention to the signaling train hereinbefore described,—an anomalous magnet, generally indicated by the number 100, is cooperatively associated with the armature 42, and the grounding contact 75 is arranged for cooperative association 120

with the main line signaling contact 48; the detailed arrangement of said parts being hereinafter more fully set forth.

The electromagnet 100 comprises three parallel legs or cores 101, 102, 103 (see Figs. 2 and 5), the strap 104 which magnetically connects one end of each of said cores with an adjacent end of the others thereof, and the windings 105 and 106 which are applied to the cores 101, and 102, respectively. The core 103 passes upwardly from the strap 104, past the adjacent ends of the windings 105 and 106, thence parallel to the cores 101 and 102, between and slightly above the peripheries of said windings, past the opposite ends thereof, thence downwardly between the ends of the cores 101 and 102, as best shown in Fig. 5. The free ends of all three of said cores are situated adjacent the normal or attracted position of the armature 42, so that said armature may be retained in such position by energization of said magnet; said windings being so proportioned that intended current flow through either one thereof will cause effective energization of said magnet.

One end of the winding 105 is connected through the conductor 107 to the signaling contact 48, and a corresponding end of the winding 106 is connected through the conductor 109 to contact 49. The remaining end of winding 105 is connected through conductor 111 to protective shunt contact 51 and the remaining end of winding 106 is connected through conductor 114 to main line terminal post 112.

The main line conductors 116 and 117 are connected to the line terminal post 112 and the protective shunt contact 51, respectively; and a conductor 118 connects said post 112 with the protective shunt contact 52.

From the foregoing it will be seen that a signaling current path is provided from the post 112, through conductor 114, winding 106, and conductor 109 to signaling contact 49, thence through said contact, and through contact 48, conductor 107, winding 105 and conductor 111 to the junction thereof at contact 51 with conductor 117; and that, when the detent lever 26 is normally positioned, a low resistance or a shunt path is provided in parallel with said signaling path from said post 112, through conductor 118, protective shunt contacts 52 and 51 to said conductor 117.

It will also be apparent that the electromagnet 100 is so constructed and arranged that current flow through the windings 105 and 106 may serve to cause either usual two pole or anomalous three pole magnetization thereof dependent upon the relative directions of flow in said windings. For example, when the direction of current flow in the winding 105 bears a certain predeter-

mined relationship to that in the winding 106, magnetism of opposite polarity will be developed at the free ends of the cores 101 and 102, and the resultant magnetic flux will pass through the armature 42 from one to the other of said cores, and thereby tend to retain said armature in attracted position; and when the direction of current flow through said winding 105 has the opposite relationship to that through said winding 106, magnetism of like polarity will be developed at the free ends of the cores 105 and 106, so that the magnetic flux will pass between one and the other of said poles and the core or leg 103 (see Fig. 2), both through the armature 42 and through the strap 104, and thus correspondingly serve to retain the armature 42 in attracted position. It will likewise be evident that the effectiveness of such magnetization will not be dependent upon the relationship of the intensity of current flow through the windings 105 and 106, as the pull resultant from current flow through one of said windings always supplements that of current flow through the other of said windings irrespective of relative differences in either or both strength and direction thereof. In the event of current flow through but one of the windings 105 and 106, the resistance of the magnetic circuit will be at minimum, because the resultant lines of force may then pass in parallel through the core 103 and the core 101 or 102 which is not then energized. For example, when there is current flow through the winding 105, but none through the winding 106, the lines of force passing between the free end of the core 101 and the armature 42 may pass between said armature and the strap 104 through the cores 102 and 103, in parallel.

The contact 75 is carried by but insulated from the governing lever 76, which lever is pivoted at 30 in common with but moving independently of the signaling lever 29. For convenience, this contact will be hereinafter referred to as a "grounding contact", although it should be understood that this contact might be connected with a conductor other than the ground, and that the term "grounding contact" is therefore intended to include any similarly arranged contact as well as any contact provided for governing any branch current path under conditions analogous to those hereinafter described in greater detail.

The spring 77 is so applied to the lever 76 as to tend to so swing same around the pivot 30 as to carry the contact 75 into engagement with the contact 48 and to maintain contact therebetween.

An insulating sleeve 78, carried by the detent lever 26, is positioned, with relation to an end of the ground-contact-governing lever 76,—so that when said detent lever is

- in the position which it assumes while the signaling train is at rest, the contact 75 will be situated somewhat above the path of the cycles of movement imparted to the contact 5 48 by the signaling lever 29; so that when said detent lever is in the position which it occupies during the running of the train, said sleeve will permit the lever 76 to so swing on its pivot 30 as to carry the contact 10 75 somewhat into the path of such cycles of movement of the contact 48, and so that said sleeve will serve to arrest the movement of said lever 76 after it has carried said contact 15 75 downwardly, in engagement with and during the portion of the cycle of the movement of said contact 48 in which the contact 49 moves downwardly in engagement therewith, so that, when at the lower end of its said cycle of movement, said contact 20 48 will be substantially equidistant from the contacts 49 and 75.

In the embodiment of this invention illustrated in the accompanying drawings, the sleeve 78 has inserted through it the terminal 25 screw for the shunt contact 52, the outer end of the sleeve being counterbored to receive the head of the screw and projecting forward a sufficient distance to bring the sleeve within the path of movement of the cooperating end of the lever 76. A pin or stud of non-insulating material if carried by an insulating block, such as the block 54, movable with the detent lever 26 and positioned so as to similarly cooperate with the end of the 30 lever 76, could be substituted for the insulating sleeve 78.

At the opposite end of the lever 76 there is a rearwardly extending projection 79 (indicated by dotted lines in Fig. 1) which projection is so situated with relation to the pin 46 that, when the lever 40 is so positioned that the pin 58 is in the path of movement of the extension 59 and the armature 42 is out of the effective range of the magnet 100, 40 said pin 46 will hold said lever 76 in such position as to support the contact 75 out of the path of the movement imparted to contact 48 by the signaling lever 29 and so that when said lever 40 is in its normal position, 45 the movement of said lever 76 in response to the spring 77 will be limited only by the sleeve 78 and the contact 48.

Fig. 2 diagrammatically indicates the manner of connecting the signal mechanism 50 of Fig. 1 in a typical signaling circuit comprising a battery A, an emergency switch B, and electromagnets C' and C'' for the control of suitable responsive instruments.

The switch B consists of the arms 91 and 55 92, which are connected by the yoke 93 and cooperate with the contacts 94 and 95; the terminals of battery A being connected to said contacts 94 and 95, respectively; the switch arm 91 being connected to the ground, 60 the switch arm 92 being connected to one

winding of the magnet C' and the switch contact 95 being connected to one winding of the magnet C''. The conductors 117 and 116 are connected through suitable line wires with the remaining windings of the magnets 70 C' and C'', respectively; and grounding contact 75 of the signal transmitting mechanism is connected to the ground through conductor 175.

Under normal conditions the switch B is 75 positioned as indicated by dotted lines in Fig. 2, thus conditioning the circuit for so-called "all metallic" operation. The operation of a signaling train such as that of Fig. 1, while the circuit is normally conditioned 80 as just described, is substantially the same as that of a well-known type of perfect non-interference and succession fire alarm signaling box, which is well understood by those skilled in this art, and will therefore not 85 be here described in detail.

In the event that the normal "all metallic" current path is broken—as by rupture of conductor 116 or conductor 117—warning will be given by the instruments controlled 90 by the magnets C' and C'' and, in accordance with usual practice in systems using circuits such as that indicated, the attendant will thereupon move the switch B from the dotted line position to the position indicated by full lines, thereby grounding one terminal of battery A and connecting conductors 116 and 117 in parallel to the other terminal of said battery.

When connected in a circuit conditioned 100 as just described, the operation of the signaling mechanism of Fig. 1—when set in motion by the actuation of the pull handle 28—is as follows:

Detent lever 26 will be elevated, thereby 105 moving contact 52 away from contact 51 so as to break the protective shunt around the windings of the electromagnet 100. Such movement of the lever 26 will also raise the insulating sleeve 78 far enough to permit 110 the lever 76 to move in response to the spring 77 until the contact 75 is brought into engagement with the contact 48, thereby 115 causing energization of the electromagnet 100 through one or the other of current paths as follows: Assuming that conductor 117 is broken, there will be a current path from one terminal of battery A, through contact 95 and arm 92 of switch B, through windings of magnet C' and conductors 116 and 114 to one end of winding 106, thence 120 through said winding and through conductor 109 and contacts 49 and 48 to contact 75, thence through conductor 175 and through the ground to arm 91 of switch B, thence 125 through said arm and contact 94 of said switch to the other terminal of battery A. Such current flow through the winding 106 will so energize the magnet 100 as to hold the armature 42 against retraction when the 130

face 55 is withdrawn from the path of the pin 46, so that the intended code signal will be formulated in the usual manner, which may be summarized as follows: When the 5 detent arm 26 has been sufficiently raised, the signaling train will start running, and thereby rotate the code wheel 23 subject to the governing action of the escapement mechanism comprising the wheel 24 and pallet 25. Such rotation of the code wheel 23 will bring the first of the code teeth carried thereby into the path of the projection 31 of the signaling lever 29 and, thereupon, the pin 33 will be withdrawn from the path 15 of the tail 32 of said signaling lever, so as to no longer prevent said lever from following the outline of said code wheel. If the electromagnet 100 remains energized until the first tooth of the code wheel 23 is withdrawn from the path of the projection 31, the signaling lever 29 will be moved downwardly in response to the tension of the contact 48, and said contact will thereupon move away from the contacts 49 and 75; 20 thereby interrupting the current path through magnet C' and magnet 100. Upon such circuit interruption, such responsive device as may be controlled by magnet C' will act in response thereto, but the armature 42 will not be permitted to move away from the magnet 100 because the downward movement of the signaling lever 29 incident to the circuit interruption, carried the extension 59 thereof into the path of the pin 58 25 and thereby held the lever 40 from movement in response to the retractile spring 47 upon deenergization of the magnet 100. The relative positions of the signaling contacts during such a circuit break are indicated by Fig. 3, and it will be understood 30 that the circuit will be alternately closed and broken in accordance with the outline of the code wheel 23 so as to correspondingly cause the manifestation of the intended code signal by such device as may be arranged for 35 response to the magnet C'.

It will be noted that during each of the movements of the contact 48 in alternately breaking and closing the circuit, as just 40 described, there will be relative movement between the cooperating portions of said contact 48 and the grounding contact 75 during engagement thereof, such as will 45 tend to assure effective electrical connection therebetween.

After a predetermined cycle of the operation of such train (usually four so-called "rounds" or revolutions of the code wheel 23) the detent lever 26 will return to its normal position and thereby move the lever 76 to the position in which the contact 75 is raised above the path of movement of the contact 48. The train will thereafter be brought to rest as soon as the wheel 21 has 65 reached the position which causes the pin 46

33 to engage the tail 32 of the signaling lever 29, and thereby cause said lever to move the signaling contact 48 to its normal position. It will be noted that because such movement of said contact will not bring same into engagement with the contact 75; the signaling circuit will be left open, so that the magnet C' may respond to the signal of any box situated in the circuit between that whose operation has just been considered and the 75 point where said circuit is ruptured.

Had the break in the circuit resulted from rupture of conductor 116—instead of that of conductor 117, as in the case just considered in detail, the operation of the various parts would correspond with that just described, except that the current flow would be through the electromagnet C'' and the winding 105, instead of through electromagnet C' and the winding 106.

Should a signaling mechanism, such as that shown in Fig. 1, be set in motion while connected in a circuit such as that indicated by Fig. 2, when the switch B is conditioned as therein shown by solid lines, but when, instead of one or the other sides of the metallic circuit being ruptured, both sides of such circuit were intact,—when the detent lever 26 was raised, in response to the manipulation of the pull handle 28, current would flow from one terminal of the battery A to contact 95 of the switch B; and from thence through two paths one of which would include the switch arm 92, the windings of electromagnet C', conductors 116 and 114, winding 106 and conductor 109, through contact 49 to contact 48,—and the other of which paths from contact 95 of switch B would include the windings of electromagnet C'', conductors 117 and 111, winding 105 and conductor 107, to contact 48; from contact 48 the two current paths would combine, passing through contact 75, conductor 175 and the ground to arm 91 of switch B; thence through said arm and contact 94 to the other terminal of battery A. It will be noted that, without this invention, such current flow through the windings 105 and 106 in parallel relationship (instead of normal series relationship) would cause one of said windings to substantially neutralize the magnetization produced by the other thereof, so that the non-interference armature would be withdrawn from the magnet 100 by the pull of the spring 47 and thereby cause the loss 115 of the intended signal; while the arrangement of the cores 101, 102 and 103 with relation to the windings 105 and 106 causes magnetic flux between the poles of the magnet 100, as diagrammatically indicated by 120 dotted lines in Fig. 2, whereby the armature 42 (and hence the non-interference mechanism controlled thereby) will be caused to respond to the anomalous three 125 pole magnetization incident to current flow 130

- through windings 105 and 106 in parallel, with effectiveness substantially equal to that with which said armature responds to the usual two pole magnetization incident to current flow through said windings in series.
- In the event that two signaling mechanisms, such as that of Fig. 1, are simultaneously set in motion while connected in a circuit such as that of Fig. 2 when the switch 10 B is positioned as indicated by dotted line so as to condition the circuit for normal "all metallic" operation,—the non-interference mechanism of one or the other of the signaling trains of such signal mechanisms will act 15 in the usual manner to so govern the effectiveness of the operation of the circuit controller thereof as to relinquish the control of such circuit thereby and thus permit the formulation of the signal of the other of 20 such boxes. To this end, the circuit controller and non-interference mechanism of such relinquishing mechanism will become positioned as shown by Fig. 4,—the signaling lever 29 being supported in elevated position by the pin 58 which is situated under the extension 59 because the armature 42 is in retracted position. Such elevation of the signaling lever 29 will maintain the circuit controller contact 48 in engagement 25 with the contact 49, and the pin 46 will support the lever 26 in such position as to prevent movement of the contact 75 into engagement with the contact 48. It will therefore be apparent that when the signal mechanism of 30 any station relinquishes control of the signaling circuit, under conditions such as just described, the grounding contact of such station will be held out of engagement with the main line contacts thereat, so that such 35 grounding contact cannot cooperate with that of the signaling mechanism of any other station (or with a ground contact at headquarters) to cause interference with or mutilation of the controlling signal.
- 40 When the armature 42 has moved to its retracted position, as just described, it will remain in such position until the end of a predetermined cycle of operation of the signaling train, whereupon the lever 26 will 45 move away from its fully elevated position. During such movement of the lever 26, the face 56 thereof will so engage the pin 46 as to move the lever 40 to a position where the projection 43 will be in the path of the pin 50 44. The shoulder 57 formed on the lever 26 will thereafter so engage the pin 46 as to prevent further downward movement of the lever 26 before the latter has moved to a position such as to cause the running of the 55 signaling train to be arrested.
- 60 It may be noted that, in a circuit such as that of Fig. 2, when the switch B is positioned as indicated by solid lines and signal mechanism of a given station, such as that of 65 Fig. 1, is causing signal formulation in such circuit, if corresponding mechanism at another station is set in motion,—should the line conductors be intact, the signal of the one of such stations which is first set in motion will be fully and correctly manifested by such responsive instrument as may be controlled by either the magnet C' or the magnet C'', depending upon the relationship of the mechanisms to one and the other of said magnets. Thus, for example, if the 70 mechanism first set in motion is situated between the magnet C' and the mechanism subsequently set in motion, such device as is arranged for response to said magnet C' will manifest the complete code signal of the station first set in motion. The current path for said manifestation is from one side of battery A through magnet C', conductor 116, conductor 109, signaling contacts 49, 48, ground contact 75 and conductor 175 of said 75 station, and thence through ground to the other side of battery A. Such device as is responsive to the magnet C'' will manifest as 80 much of the same signal as is formulated before the mechanism of the second station is set in motion, the current path for such manifestation being from one side of battery A through magnet C'', conductor 117 to shunt contacts 51, 52 of said second mentioned station, thence through conductor 118 and terminal post 112 to conductor 114, magnet 106, conductor 109, signaling contact 49, ground contact 75 and conductor 175 of said 85 first mentioned station, and thence through ground to the other side of battery A. Following the manifestation of the signal at the said first station, the device responsive to the magnet C'' will manifest the full and 90 complete signal of such second station, the current path for such manifestation being from one side of the battery A through the magnet C'', conductor 117, conductor 111, magnet 105, conductor 107, signaling contact 48, ground contact 75 and conductor 175 of said 95 second mentioned station, and thence through ground to the other side of battery A. If one of the line conductors, as, for example, the conductor 116, is ruptured at the time that the two transmitting mechanisms of two stations are 100 currently in action, as just described, and if one of said mechanisms is at one side and the other at the opposite side of such break, the signal will be manifested by the devices 105 responsive to the magnets C' and C'' respectively. Under such conditions the current path for the manifestation of the signal from the first of such stations is from one side of the battery A through the magnet C', conductor 116, thence through conductor 114, magnet 106, conductor 109, signaling contacts 49, 48, ground contact 75 and conductor 175 of said first station, and 110 thence through ground to the other side of 115 battery A. The current path for the manifestation of the signal from the second station is from one side of the battery A through the magnet C'', conductor 117, conductor 111, magnet 105, conductor 107, signaling contact 48, ground contact 75 and conductor 175 of said second mentioned station, and thence through ground to the other side of battery A. Under such conditions the current path for the manifestation of the signal from the second station is from one side of the battery A through the magnet C'', conductor 117, conductor 111, magnet 105, conductor 107, signaling contact 48, ground contact 75 and conductor 175 of said second mentioned station, and thence through ground to the other side of battery A.
- 120
- 125
- 130

- battery A. The current path for the manifestation of the signal from the other of said stations is from the opposite side of said battery A through magnet C", conductor 117, thence through conductor 111, magnet 105, conductor 107, signaling contact 48, ground contact 75 and conductor 175 of said other of said stations, and thence through ground to the other side of said battery A.
- 10 If both of such mechanisms are situated at one side of the point where the circuit is ruptured, and if the mechanism of the station furthest from the break is first set in motion, no mutilation or overlapping of signals will result from subsequently setting in motion mechanisms from other stations situated in the circuit between such first operated station and the break, because the current path from any such other station is interrupted on one side by said break and on the other side by the signaling contacts 48 and 49 of said first operated station. But if the mechanism is set in motion at a station which is situated in the circuit between a previously operated station and the receiving magnet responsive thereto, while the switch B is positioned as shown in full lines in Fig. 2, the signal of such first operated station will be cut off pending the formulation of the signal of such subsequently operated station because the current path from said first operated station will be interrupted by the signaling contacts 48 and 49 of such subsequently operated station. In like manner, it may be observed that, when the switch B of Fig. 2 is normally positioned, (as indicated by the dotted lines) and the formulation of the signal of any one station having mechanism such as that of Fig. 1 is in progress, if similar mechanism situated at each side thereof in the circuit is set in motion,—the transmitting mechanisms of each of such other stations will apply its ground and thus temporarily prevent the mechanism 45 of the station first set in motion from effectively breaking the circuit. Thereupon, the armature 42 of the station first set in motion would drop away from its magnet, and a determination would be made by the non-interference mechanism of the remaining two active stations, in a manner which is well understood by those skilled in this art, as to which of such transmitters should proceed with its signal.
- 50 Inasmuch as the conditions under which signal mutilation may occur when using transmitting mechanisms such as that of Fig. 1, as just referred to, may, in certain signaling systems, be considered to be so unlikely of occurrence as to be negligible, the mechanism illustratively shown in Fig. 1 may be employed in some such systems notwithstanding the opportunities for interference thereby afforded; but it should be understood that this particular form of mechanism was selected for use in illustrating this invention, notwithstanding such more or less remote possibilities of interference, because this mechanism is much more simple and readily understood, and therefore susceptible of illustration by means of fewer drawings and explanation by a less extended description than would be necessary had some other prior art form of signaling mechanism been shown with this invention applied thereto, and it is believed that, in view of the foregoing detailed description, the manner of applying this invention to other prior art signaling mechanisms will be apparent to those skilled in this art.
- 55 Since many matters of combination, arrangement, structure, design and detail may be modified without departing from the underlying principles, and various features of this invention may be advantageously employed without the utilization of all of such features, it should be understood that the invention is not restricted to such features except so far as specified in the appended claims, and that the language used in said claims is intended to cover all of the generic and specific features of the invention herein described and all statements of the scope of the invention, which, as a matter of language, might be said to fall therebetween.
- 60 Having thus described my invention, what I claim as new and desire to secure by Letters Patent of the United States of America is:
1. In a signal transmitter, a signaling train, a member for conditioning said train for operation, a code-wheel operable by said train, a circuit controller operable by said code-wheel to open and close a current path therethrough, an electromagnet having three cores and two windings for respective ones of said cores, said circuit controller being included between said windings, the third of said cores being so related to said two cores as to provide a path for lines of magnetic force from either of said windings, an armature arranged for cooperation with all three of said cores and pivotally mounted for movement into and out of the effective range of the attraction of said cores, means for holding said armature against movement out of such effective range during conditioning of said circuit controller to open the current path therethrough and for holding said controller against opening such path when said armature is out of such effective range, a contact movable to either of two positions for grounding said circuit controller upon each operation thereof by said code wheel only when said contact is in one of its said positions, and means for governing the positioning of said contact.
  2. In a signal transmitter, a signaling train, a detent member for said train, an

- electromagnet having three cores and two windings for respective ones of said cores, the third of said cores being so related to said two cores as to provide a path for lines of magnetic force for either of said windings, a circuit controller operable by said train and connected between said windings, non-interference mechanism responsive to said electromagnet for governing the effectiveness of the actuation of said circuit controller by said train, a contact for grounding said circuit controller upon each operation thereof by said train only during predetermined conditioning of said contact, and means responsive to said detent member and to said non-interference mechanism for at times avoiding such conditioning of said contact.
3. In a signal transmitter, an electromagnet having three cores and two windings carried by respective ones of two of said cores, the third of said cores being so related to said two cores as to provide a path for lines of magnetic force from either of said windings, non-interference mechanism comprising an armature cooperating with all of said cores, a circuit controller connected between said windings, and a ground branch contact for cooperation with said circuit controller.
4. A signal transmitter having a normally closed metallic circuit current path and a normally open ground branch in combination with non-interference mechanism comprising an electromagnet having a plurality of windings, a circuit controller governed by said magnet and having means for breaking said normally closed path and for closing said path in conjunction with said branch, said circuit controller being located between said windings, and said electromagnet having provision for effective energization thereof from current flow either serially through said windings and said normally closed path or in parallel through said windings and said normally open ground branch, irrespective of the relative directions of current flow through such windings.
5. In a signal transmitter, a signaling train, a circuit controller comprising three contacts operable by said train for alternately closing and breaking the electrical connection therebetween, non-interference mechanism for governing the effectiveness of operation of said contacts by said train and comprising an electromagnet having three cores and two windings for respective ones of two of said cores, the third core being so related to said two cores as to provide a path for lines of magnetic force from either of said windings, said windings being so connected to respective ones of two of said circuit controller contacts whereby they are effectively energized upon current

flow either serially through said windings and said two contacts or in parallel through said two windings and the third of said contacts.

6. In a signal transmitter, non-interference mechanism comprising an electromagnet having two windings, a circuit controller located between said windings for governing the connection therebetween and for establishing a ground connection therewith, and provision for rendering said windings functionally effective both for relative differences in current strength and in direction of current path therein.

7. In a signal transmitter, non-interference mechanism comprising an electromagnet having two windings, a circuit controller located between said windings for governing the connection therebetween and for establishing a ground connection therewith, and provision for rendering the resultant magnetism of said windings substantially equivalent in effectiveness in the control of said mechanism for different relative directions of current flow in said windings.

8. In a signal transmitter, an electromagnet having two windings, said magnet including means whereby current flow through said windings may serve to cause either usual two pole or anomalous three pole magnetization thereof, dependent upon the relative directions of flow in said windings, and non-interference mechanism arranged for response to either such two pole or three pole energization of said magnet.

9. A signal transmitting apparatus having a detent member for controlling the operation thereof, a code wheel and a signaling contact operable thereby in combination with a grounding contact movable into or out of the operative path of said signaling contact, an electromagnet, an armature pivotally mounted for movement into and out of the effective range of the attraction of said magnet, means for holding said armature against movement out of effective range during the conditioning of said circuit controller to open the current path therethrough and for holding said controller against opening such path when said armature is out of such effective range, a controlling lever for said grounding contact, one end of said lever being so disposed in the path of a part moving with said detent member that normal positioning of said member will cause positioning of said grounding contact out of the operative path of the circuit controller contact cooperating therewith, and the other end of said lever cooperating with the part moving with said armature so as to permit said grounding contact to be disposed in the operative path of the circuit controller contact associated therewith only when said armature is disposed within the effective range of said magnet, and means urging

100

movement of said grounding contact into the path of said circuit controller contact cooperating therewith.

10. A signal transmitting apparatus having a signaling train, a member for conditioning said train for operation, a code-wheel operable by said train, a circuit controller operable by said code-wheel to open or close a current path therethrough, an electromagnet, an armature pivotally mounted for movement into and out of the effective range of the attraction of said magnet, means for holding said armature against movement out of such effective range during the conditioning of such circuit controller to open the current path therethrough and for holding said controller against opening such path when said armature is out of such effective range, a grounding contact with which said circuit controller may functionally cooperate, a lever movable for governing said functional cooperation, one end of said lever being so disposed in the path of a part moving with said conditioning member that normal positioning of the latter will prevent such functional cooperation, and the other end of said lever so cooperating with the part moving with said armature as to permit said functional cooperation only when said armature is disposed within the effective range of said magnet.

11. A signal transmitting apparatus having a detent member controlling the operation thereof, a code-wheel and a signaling contact operable in a predetermined path thereby, in combination with a ground contact movable into or out of such path of said signaling contact, and controlling means for said grounding contact disposed in the path of a part moving with said detent member so as to permit movement of said grounding contact into such path of said signaling contact only while said detent member is ineffectively positioned.

12. In a signal transmitter, a signaling train, a member for conditioning said train for operation, non-interference mechanism comprising two electromagnet windings, a circuit controller operable by said train and connected between said windings, a ground branch contact movable into and out of cooperative relation with said circuit controller, means urging movement of said contact into cooperative relationship with said controller, and means subject to joint control by said member and said non-interference mechanism for holding said contact out of such cooperative relationship.

13. In a signal transmitter, a signaling train, a member for conditioning said train for operation, a code wheel operable by said train, a circuit controller operable by said code wheel, non-interference mechanism

comprising two electromagnet windings between which said controller is connected, a grounding contact with which said controller may functionally cooperate, and means for governing such functional cooperation, said means being positionally so related to said member and said non-interference mechanism as to be subject to the joint control thereof.

14. Signal transmitting apparatus having a main line signaling contact and a code wheel for imparting cycles of movement to said contact in a predetermined path, in combination with a grounding contact movable both in and out of said path, means urging movement of said grounding contact in said path toward said main line contact, and means for suitably limiting such movement and for at times causing movement of said grounding contact out of the path of said main line contact.

15. Signal transmitting apparatus having a member for controlling the operation thereof, a code wheel, a signaling contact operable in a predetermined path thereby, and non-interference mechanism; in combination with a grounding contact movable into or out of such path of said signaling contact, and controlling means for said grounding contact so governed by engagement with a part connected to said member and by said non-interference mechanism that said grounding contact will be moved into such path of said signaling contact only while said member is ineffectively positioned and said non-interference mechanism is conditioned to permit signal formulation.

16. Signal transmitting apparatus having a member for controlling the operation thereof, a code wheel, and a signaling contact operable in a predetermined path thereby; in combination with a grounding contact movable into or out of such path of said signaling contact, and controlling means for said grounding contact so governed by engagement with a part connected to said member as to permit movement of said grounding contact into such path of said signaling contact only while said member is ineffectively positioned.

17. Signal transmitting apparatus having a member for controlling the operation thereof, a code wheel and a signaling contact operable in a predetermined path thereby; in combination with a grounding contact movable into or out of such path, said grounding contact having governing means positionally so associated with said member that such movement of said contact may be governed thereby.

In witness whereof, I hereunto subscribe my name, this third day of September, 1924.

NATHAN H. SUREN.
